[57] ABSTRACT

The granulator has a hollow knife cylinder with knife edges extending from end to end. The plastics strands are fed in transversely to the longitudinal axis of the cylinder while the cylinder and strands are moved relative to one another longitudinally of the cylinder. The bearing system of at least one end of the cylinder is disposed within the cylinder. At this end, the cylinder is provided with an inclined surface projecting beyond the cylinder in the axial direction; the imaginary elongation of this surface meets or intersects the end of the path of the knife edges.

GRANULATOR FOR GRANULATING PLASTIC STRANDS

The invention relates to a granulator for granulating plastics strands, provided with a hollow knife cylinder, journalled at both ends and having knife edges extending from end to end. The longitudinal axis of the knife cylinder extends approximately perpendicularly to the in-fed plastics strands, and the knife cylinder and plastics strands traversed relative to each other longitudinally of the cylinder axis.

The prior art discloses a granulator of the kind described above which is traversable on rails transversely to the in-fed plastics strands and accordingly, when operation is started, is moved into the path of the plastics strands, which are delivered by a cooling plant. Relatively large bearing houses are provided on both ends of the knife cylinder in known granulators, these bearing housings causing difficulties in terms of motion into the path of the in-fed plastics strands because these strands initially strike the bearing housings instead of engaging the knife cylinder. This also applies to a slideable granulator which has also been proposed and incorporates two knife cylinders which are alternately operated.

It would therefore be desirable to provide a granulator which could be moved laterally into the path of the in-fed plastics strands without obstructing the feed of such strands, thus ensuring a reliable start of the granulating operation.

This is achieved by disposing the bearing system of at least one end of the knife cylinder in the interior of the cylinder and providing this end-face of the knife cylinder with an inclined surface which extends beyond the knife cylinder in the axial direction and forms an acute angle with the plastics strands so that their imaginary elongation meets the ends of the knife edges of the knife cylinder or intersects therewith.

On the one hand, no bearing housing obstructs the feed of the strands when the granulator is moved into the path of the plastics strands and, on the other hand, these strands are deflected by the inclined surface so that they are reliably cut by the knife edges at the end of the knife cylinder and the process of granulation may start without complications. The application of the basic idea of the invention is particularly advantageous in respect of the known granulator with two knife cylinders, the inclined surfaces being then provided on the inwardly facing end-faces of the two knife cylinders.

To ensure that the plastics strands, which are not particularly resistant to bending because of their small cross-section, are guided (with respect to the vertical direction) so that they assume the optimum position with respect to the cutting edges of the knife cylinder as required for end granulation it is advisable to form the inclined surface by providing a progressively deepening groove in one end plate which closes the end-face of the knife cylinder or its bearing system, the said groove extending in the direction of the in-fed plastics strands. The lower flank of the groove then functions as a guide for the plastics strands. To the same end, it is also advisable if the lower flank of the groove is in alignment with a support for the plastics strands disposed upstream of the knife cylinder. A support of this kind is already provided in conventional granulators.

In a preferred embodiment, the bearing housing on the end of the knife cylinder which has the inclined surface is provided with an outrigger or extension in the

form of a circular section or annular circular sector for mounting the bearing system on a machine frame, so that the mounting means for the bearing systems which have been displaced into the interior of the knife cylinder do not obstruct the feed of the plastics strands. This outrigger may be constructed shallower than half the height of the knife cylinder so that it does not obstruct the plastics strands which are fed in approximately into the horizontal median plane when the granulator is moved into the path of the strands.

The granulator may of course also be fixedly disposed and the plant which delivers the plastics strands to the granulator, that is to say usually the cooling plant, may be slidably constructed, but it is usually simpler to provide a fixed cooling plant and a slideable granulator.

The invention will be described further, by way of example only, with reference to the accompanying drawings, in which:

FIG. 1 is a diagrammatic side view of a plant for producing plastics granulate;

FIG. 2 is a section through the essential parts of the granulator of this plant, taken along the line 2-2 of FIG. 1;

FIG. 3 is a side view of the granulator and

FIG. 4 is a section through part of the granulator, taken along the line 4-4 of FIG. 3.

FIG. 1 shows in diagrammatic form an extruder head 10 from the bottom of which a row of plastics strands are extruded. These pass through a cooling plant 12 filled with water, through which the plastics strands are conveyed by means of conveyor belts 14. A pair of delivery rollers 16 is disposed at the right-hand end of the cooling plant as seen in FIG. 1; this roller pair delivers the solidified plastics strands to a granulator 18.

The drive of the granulator 18 is housed in a motor casing 20, which supports a machine frame 22. The entire granulator is carried by wheels (not shown) running on rails 24, so that it is traversable perpendicularly to the plane of the drawing (FIG. 1). A knife cylinder 26 is journalled on the machine frame 22 so as to be rotatable about an axis which is perpendicular to the plane of the drawing (FIG. 1); the knife cylinder is driven via a transmission (not shown) - by the motor in the motor casing 20 and is covered by a hood 28. The granulated plastics passes through a discharge trough 30 into a collecting container 32.

FIG. 2 shows the detailed construction of the granulator in the region of the knife cylinder 26. Two bearing systems 34 and 36 are mounted on the machine frame 22, the shaft 38 of the knife cylinder 26 being rotatably journalled in these bearing systems. The knife cylinder shaft 38 carries two discs 40 and 42 on which a support cylinder 44 is mounted. The cylinder 44 supports a knife cylinder 46 having cutting edges 48 which extend longitudinally as far as the ends of the knife cylinder.

The left-hand bearing system 34 of the shaft 38, as viewed in FIG. 2 is conventionally constructed and it is therefore not necessary to describe it in detail. The right-hand bearing system 36, which comprises a bearing housing 50 in several parts and a rolling bearing 52, is disposed substantially within the knife cylinder 46 so that merely a bearing housing cover 54 and a bearing housing collar 56 extend slightly beyond the knife cylinder 46. As may be clearly seen by reference to FIGS. 2 and 4, the bearing housing collar 56 is provided with a shell 60 for mounting the bearing 36 on the machine

frame 22, the bearing shell being secured on the machine frame by means of claws 62.

In addition, FIG. 3 shows an anvil 64 on which the plastics strands bear when they are granulated by the knife cylinder 46 as they are fed in by the delivery rollers 16 (FIG. 1).

The bearing housing cover 54 has a tapering groove 70 (see FIGS. 3 and 4) whose lower flank 70a is in alignment with the support surface 64a of the anvil 64 and whose base 70b extends at an angle so that plastics strands 80 (shown in dash-dot lines in FIG. 4) bearing on the base 70b are reliably gripped and cut off by the ends of the cutting edges 48 when the granulator is moved from left to right (FIG. 2) into the path of the plastics strands which are advanced by the delivery rollers 16 (FIG. 1), thus initiating the process of granulating. The bearing housing 50 of the illustrated embodiment is constructed so that its collar 56 also has a groove 82, which serves as a guide groove; its lower flank 82a is also in alignment with the support surface 64a.

The grooves 70 and 82 therefore prevent the plastics strands from bearing flat against the end-face of the knife cylinder 46, where they could not be engaged by the cutting edges 48 when the granulator is moved into the path of the plastics strands. It can also be seen from FIG. 3 that the shell 60 is not so tall as to obstruct the feed of the plastics strands when the granulator is moved into their path from the side.

I claim:

1. A granulator for granulating plastics strands, comprising a hollow knife cylinder, having a bearing system at each end and having longitudinal knife edges extending from end to end, the plastics strands being fed in transversely to the longitudinal axis of the knife cylinder while the knife cylinder and plastics strands are movable relative to each other longitudinally of the said axis, the bearing system of at least one end of the knife cylinder being disposed in the interior of the cylinder, the end-face of the knife cylinder at the said end being provided with an inclined surface which projects beyond the knife cylinder in the axial direction and forms an acute angle with radial direction, the imaginary elongation of the inclined surface meeting or intersecting the end of the path of the knife edges of the knife cylinder, whereby the plastics strands come successively into the path of the knife edges without being obstructed by the bearing system.

2. A granulator as claimed in claim 1, in which the said inclined surface is formed by the base of a transverse groove in the said end-face, the depth of the groove increasing in the radial direction.

3. A granulator as claimed in claim 2, further comprising a support for plastics strands entering the granulator, the groove having a flank which is in alignment with the support.

4. A granulator as claimed in claim 1, in which the said bearing system has a casing including an extension for mounting the bearing on a machine frame.
